TOY SPARKING CANNON OR THE LIKE

Walter J. Burchett, East Orange, N. J., assignor to
Art Metal Works, Inc., a corporation of New Jersey

Application December 6, 1941, Serial No. 421,885

2 Claims. (Cl. 46—10)

My invention relates to toy vehicles particularly of the type known as toy cannons or toy guns.

My invention has particular reference to a toy cannon embodying novel mechanism for firing a toy projectile or missile; more particularly, my invention relates to a toy sparking cannon comprising novel mechanism for simultaneously firing the toy cannon and producing a shower of sparks at a desired location with respect to the cannon barrel.

My invention has further reference to a novel toy bullet, projectile or missile having the nose thereof equipped with a small mass of yieldable or cushioning material which serves to prevent damage to an object struck thereby.

My invention has further reference to toy wheels of novel character and, more particularly, toy wheels which, in the peripheral area thereof, simulate the appearance of an automobile tire.

Further objects, advantages and features of my invention will become apparent from the following detailed description.

For an understanding of my invention and for an illustration of one of the forms thereof, reference is to be had to the accompanying drawings, in which:

Figs. 1 and 2 are perspective views showing the toy sparking cannon of my invention;

Fig. 3 is a longitudinal, vertical sectional view, partly in elevation, of the toy cannon shown in Figs. 1 and 2;

Fig. 4 is a transverse, vertical sectional view, partly in elevation, taken on the line 4—4 of Fig. 3 looking in the direction of the arrows;

Fig. 5 is a bottom plan view showing a part of the mechanism illustrated in Fig. 1;

Figs. 6 and 7 are sectional views showing toy wheels as constructed in accordance with my invention; and

Fig. 8 is a sectional view showing a toy bullet, projectile or missile.

Referring to Figs. 1 and 2, the toy cannon herein illustrated is shown as comprising a pair of wheels W, W rotatable on an axle 1 to which is secured the cannon trail T and on which is pivotally movable the breech B having the cannon barrel B1 extending therefrom.

The trail T simulates an actual cannon structure of this character. Between and to the rear of the wheels W, it is slotted as indicated at 2 to provide a passage in which the breech B is vertically movable as hereinafter described. At the rear end thereof, the trail T may be bifurcated

so as to pivotally support the eyelet 3. Preferably, although not necessarily, the trail T is formed from wood and, preferably, rows of tacks 4 or the like are driven thereinto in order to produce an effect resembling actual structures of this general character.

In the slot 2 of the trail T and between the wheels W, the axle 1 has a freely oscillatory sleeve 5 disposed thereon, said sleeve 5, at each end thereof, having a plate 6 secured thereto, the plates 6 extending upwardly in parallel relation and being joined together by a transverse plate 7 which, on its rear surface, is engaged by a flat plate 8.

The plates 7 and 8 are secured together in any suitable manner. To this end, for example, the upper end of the plate 7 may terminate in sleeves 7a between which is disposed a sleeve 8a forming the upper part of the plate 8, these sleeves being aligned for the reception of a connecting pin 9. In addition, the plates 7 and 8 should be secured together by lower screws 10.

The breech housing comprises side walls 11 and 11, a top wall 12, a rear wall 13 and a bottom wall 14, these walls being secured to each other in housing-forming relation in any suitable manner. As shown in Fig. 1, the top wall 12 comprises a vertical section which is secured to the plate 8 by rivets 15 or the like. In addition, those surfaces of the side walls 11, 11 together with the bottom wall 14 which engage the plate 8 should be soldered or otherwise suitably secured to said plate 8.

The barrel B1 comprises a rear block section 16 having vertical exterior surfaces disposed between the plates 6 and secured thereto by screws 60 or the like. In this manner, said barrel B1 is supported in proper relation with respect to the breech B. The barrel block section 16 comprises a vertical passage 17 aligned, in the lower area thereof, with the bore of the barrel, the passage 17 serving as a means for introducing the toy projectile or missile P into firing position.

The side walls 11, 11 of the breech B support two horizontal members 18 and 19, Fig. 3, the member 18 pivotally supporting an actuating lever 20 and the member 19 pivotally supporting a latching lever 21. The lever 20 is suitably biased in a clockwise direction, Fig. 3, by a heavy or "power" spring 22 and the lever 21 is biased in the same direction, Fig. 1, by a light spring 23.

The actuating lever 20 comprises a forward flat surface to which is suitably secured the base 24 of a hammer 25 adapted to engage the rear sur-

face of and fire the projectile P as hereinafter described. The plates 7 and 8 are provided with a passage through which the hammer 25 thus moves into firing position and the rear surface of the plate 8 around this passage forms a stop surface to be engaged by the hammer base 24 whereby movement of the actuating lever 20 in a clockwise direction, Fig. 3, is limited as shown by the broken line position thereof. The upper end of the lever 20 extends through a slot 12a formed longitudinally in the top breech wall 12 whereby said lever 20 may be moved to cocked position as hereinafter described.

The lever 20 comprises a latching section 20a with which the locking section 21a of the lever 21 is automatically engageable when the lever 20 is moved to the cocked position thereof shown by the full lines in Fig. 3. The lever 21 comprises an actuating section extending through a slot 13a provided therefor in the rear breech wall 13. In addition, for firing purposes, the actuating lever 21 has one end of a cord 26 or other flexible element secured thereto, the cord 26 extending through an opening provided therefor in the rear breech wall 13 and, preferably, through an eyelet 21 carried by the trail T, the cord 26 carrying a knob or ball 27a at the end thereof, Fig. 1.

The trail T carries a bracket 28 having a vertical section forming a bearing for a horizontal shaft 29 terminating at one end in a crank arm 28a, the other end of the shaft 29 being threaded for coaction with an interiorly threaded passage extending through a member 30 secured to one of the aforesaid plates 6.

In accordance with the invention, the barrel B1, at the end thereof removed from the breech E, has a housing member 31 suitably secured thereto and, if desired, the housing member 31 may carry a gun sight 32. As shown in Fig. 4, the lower surface of the barrel B1 may be cut away to provide space for a pyrophoric sparking mechanism which is carried by the housing member 31 in an offset extension thereof. The serrated wheel 33 and the ratchet wheel 34 of this mechanism are rotatable as a unit on a vertical pin 35 secured to said housing member 31 which, transversely of the serrated wheel 33, carries a tube 36 having a pyrophoric sparking element 37 projecting from one end thereof and biased against said serrated wheel 33 by a spring 38 confined within the tube 36, said spring 38 being held under compression by a cap 39 threaded to said tube 36.

The barrel B1, longitudinally thereof and along its lower surface, is provided with a downwardly facing slot 40 in which is disposed a reciprocating bar 41 having, at one end thereof, ratchet teeth 42 coactable with the ratchet wheel 34, this end of the bar 41 being seated upon the lower surface of the housing member 31, Fig. 4. Adjacent its other end, the bar 41 is supported for reciprocating movement in a supporting plate 43 secured by screws 44 to the front surface of the aforesaid block section 16 of the barrel B1. To the left of the supporting plate 43, Fig. 3, the bar 41 extends freely through a passage provided in the plates 7 and 8 just below the passage described above for the reception of the hammer 25, the end of the bar 41 toward the left, Fig. 3, being engaged by the hammer base 24, as herein-after described, when the actuating lever 20 moves to firing position.

The bar 41 should be biased from right to left, Fig. 3, and, to this end, a helical spring 46 may have one of its ends secured to said bar 41 and

the other of its ends secured to the aforesaid supporting plate 43.

The arrangement is such that, when the bar 41 moves from left to right, Fig. 3, the ratchet teeth 42 thereof lock with the ratchet wheel 34 to produce a step of rotative movement of the serrated wheel 33. When the bar 41 moves from right to left, Fig. 3, the ratchet teeth 42 thereof should idle with respect to the ratchet wheel 34. To this end, the end of the bar 41 carrying the ratchet teeth 42 should be capable of limited movement on its seat in the housing member 31 toward and from the ratchet wheel 34. A spring 47, seated and secured in the slot 40, engages the bar 41 at one of its ends and biases that end thereof carrying the ratchet teeth 42 in such direction that said ratchet teeth tend to remain in engagement with the ratchet wheel 34.

As shown in Figs. 1 and 2, an upstanding plate member 48 may be secured to the plates 6 by screws 49. This plate member 48 is slotted so that it embraces the block section 16 of the barrel B1 and, as will be obvious, it simulates the shield of an actual cannon of this general character.

In accordance with the invention and as shown in Figs. 1, 2 and 5, each of the wheels W is formed from wood or equivalent material which may be cut to the desired shape to form hubs, flanges, etc., the peripheral area of each wheel being formed with radial grooves 50. With the wheel periphery painted black and with the inner part of the wheel painted a contrasting color, the black grooved peripheral area of the wheel effectively simulates an automobile tire in appearance. This effect may be enhanced by associating a rubber band 51 with the outer surface of each wheel, this rubber being stretched and, while stretched, applied to the outer wheel surface as indicated whereby the rubber band inherently tends to and does remain in proper position on the outer wheel surface so as to form the tread of the wheel. As shown in Figs. 1 and 2, each wheel W, concentrically with respect to the axle, 45 may have tacks 52 driven thereinto, these tacks simulating the usual row of bolts with which an automobile wheel is equipped.

In lieu of wood, it shall be understood that the wheels of my invention may be constructed of other material. Thus, in Fig. 7, I have shown a wheel W1 formed from molded or casted members 53 formed usually from metallic material, the shape and configuration thereof being as desired. These members may be formed separately and then welded or otherwise suitably secured together so as to form a wheel structure simulating a combined automobile wheel and tire in appearance. As with the wheels W, the wheel W1 may have a tread-forming elastic band 54 disposed on the extreme outer surface thereof.

As regards the wheels W, W1 of my invention, it shall be understood that they are not to be limited to use on a toy cannon as herein disclosed. As well, such wheels may be used on other vehicles such as toy wagons, toy automobiles, etc.

Referring to Fig. 8, I have shown a projectile, bullet or missile P adapted to be propelled or shot from the toy cannon herein disclosed. As illustrated, the projectile P is a solid structure 55 generally of cylindrical configuration and provided with a tapered nose 55a having a passage in which a piece of cushioning material 56 such as thread, wicking or the like is suitably secured.

The projectile P should be formed from wood or other equivalent light-weight material.

As hereinbefore stated, the trail T, preferably, is formed from wood or the like. The barrel B1, likewise, and preferably, is formed from similar material. The plates 6, 7 and 8 together with the breech walls, preferably, are formed from sheet metal. In any event, the distribution of weight should be such that the trail T counterbalances the other parts and causes the barrel B1 to assume an elevated position. With the toy cannon thus normally positioned, the shaft 29 may be rotated in one direction or the other by actuation of the crank arm 29a to move the member 33 along the shaft 29 and thereby change the angle of inclination of the barrel B1.

In order to shoot the toy cannon, the upper end of the actuating lever 20 is moved by thumb or finger pressure from the broken line to the full line position thereof shown in Fig. 3 whereupon the lever 21, automatically, becomes effective to releasably lock said actuating lever 20 in the position last noted. At this time, a projectile or bullet P is dropped downwardly through the passage 17 of the block 16 and comes to rest in the position shown by the dotted lines in Fig. 3. Thereupon, either the cord 26 is pulled or the actuating section of the lever 21 is moved downwardly to swing said lever 21 in a counter-clockwise direction, Fig. 3, and release the actuating lever 20. The latter, under the influence of the energy stored in its spring 22, swings in a clockwise direction, Fig. 3, with a snapping action and the hammer 25 carried thereby engages the rear surface of the projectile P and propels or shoots the same from the cannon barrel B1.

Simultaneously, the hammer base 24 engages that end of the bar 41 toward the left, Fig. 3, to move said bar 41 from left to right, Fig. 3, by a snapping action and impart a quick step of rotative movement to the ratchet wheel 34 and the serrated wheel 33, the latter coacting with the pyrophoric element 37 to produce a shower of sparks at the end of the barrel B1. This occurs simultaneously with the ejection of the projectile P from said barrel B1 and effectively creates the illusion of a burst of sparks or flame at the end of the cannon barrel.

When the actuating lever 20 is returned to cocked position as shown in Fig. 3, the bar 41 moves from right to left, Fig. 3, under the influence of energy stored in the spring 46 when said bar 41 was moved in the opposite direction

during the firing operation. During such movement of the bar 41 from right to left, the end thereof carrying the ratchet teeth moves laterally against the force of the spring 47 to permit 5 said ratchet teeth to idle with respect to the ratchet wheel 34. This operation places the sparking mechanism in condition for subsequent operation in the manner described above.

While the invention has been described with 10 respect to a certain particular preferred example which gives satisfactory results, it will be understood by those skilled in the art after understanding the invention, that various changes and modifications may be made without departing 15 from the spirit and scope of the invention and it is intended therefore in the appended claims to cover all such changes and modifications.

What is claimed as new and desired to be secured by Letters Patent is:

- 20 1. In a toy sparking cannon, a breech housing, a barrel projecting therefrom and adapted to have a toy projectile disposed therein in firing position, spark-producing means disposed adjacent the discharge end of said barrel, an actuating member disposed within said breech housing and movable from a cocked position to a firing position for firing the toy projectile from said barrel, means disposed within said breech housing for holding the actuating member in cocked position, and a rod extending from said breech housing to the spark-producing means, said actuating member engaging said rod and operating said spark-producing means as it moves toward firing position.
- 25 2. In a toy sparking cannon, a breech housing, a barrel projecting therefrom and adapted to have a toy projectile disposed therein in firing position, pyrophoric spark-producing means disposed adjacent the discharge end of said barrel, an actuating member disposed within said breech housing and movable from a cocked position to a firing position for firing the toy projectile from said barrel, means for holding the actuating member in cocked position, a reciprocatory rod 30 terminating at one end in said breech housing and extending along said barrel to the spark-producing means, and a spring for biasing said rod toward said breech housing, said actuating member engaging said rod and moving it against the force of said spring to operate said spark-producing means as it moves toward firing position.

WALTER J. BURCHETT.
